UNITED STATES PATENT OFFICE.

CLARENCE J. COBERLY, OF LOS ANGELES, CALIFORNIA, ASSIGNOR TO CALIFORNIA BURDETT OXYGEN COMPANY, A CORPORATION OF CALIFORNIA.

PROCESS OF AND APPARATUS FOR CUTTING METALS.

Application filed June 8, 1920. Serial No. 387,486.

To all whom it may concern:

Be it known that I, CLARENCE J. COBERLY, a citizen of the United States, residing at Los Angeles, county of Los Angeles, and ⁵ State of California, have invented a new and useful Process of and Apparatus for Cutting Metals, of which the following is a specification.

My invention relates to the art of cutting metals by oxygen. It is the present practice in this art to heat the metal so that it becomes incandescent preferably by an oxy-hydrogen flame and to then supply to the heated metal a jet of oxygen which unites ¹⁰ with the metal forming an oxide which is blown away leaving an open space.

The principal object of my invention is to produce an apparatus which will cut metal much more rapidly and at a greater ¹⁵ efficiency than it is at present possible.

A further object of my invention is to provide a process and apparatus by which materials may be cut which are at present found to be impractical.

²⁵ Further objects and advantages will be made more evident hereinafter.

Referring to the drawings which are for illustrative purposes only,

Fig. 1 is a section through a diagrammatic form of my invention.

Fig. 2 is a top view of same.

Fig. 3 is a section on a plane represented by the line 3—3 of Fig. 1.

Fig. 4 is a section on a plane represented ³⁵ by the line 4—4 of Fig. 1.

Fig. 5 is an alternate form of my invention.

Fig. 6 is a section on a plane represented by the line 6—6 of Fig. 5.

Fig. 7 is a section on a plane represented by the line 7—7 of Fig. 5.

In the form of my invention illustrated in Figs. 1 to 4, 11 is a body, having an oxygen passage 12 and a hydrogen passage ⁴⁵ 13 formed therein, these passages communicating with suitable sources of supply through flexible tubing, not shown. Valves 14 and 15 control the supply of gas in the passages 12 and 13, these valves being opened together by means of a screw 16 and a cross bar 17 against the action of compression springs 18. The passage 13 communicates with a manifold 20 connecting through small passages 21 with a hydrogen chamber 22. The hydrogen chamber 22 is formed

between a shell 23 and a tube 24, the shell 23 is threaded on the body 11 and clamps the tube 24, as shown. This tube 24 is preferably formed of zirconium or cerium oxide, being formed by mixing these oxides with ⁶⁰ an organic binder which is destroyed during the subsequent baking operations leaving the tubes full of minute holes.

The method of operation of this form of my invention is as follows:

A small amount of oxygen and hydrogen being supplied to the passages 12 and 13 by a slight opening of the valves 14 and 15 the hydrogen passes from the chamber 22 into the interior of the tubes through the walls thereof mixing with the oxygen delivered through the passages 12 and when ignited producing a flame outside the lower end of the tube as shown at 25. Due to the slow velocity of the gases, this flame flashes back ⁷⁰ into the tube 24 and surface combustion is started on the inner walls of this tube, the hydrogen passing through the tube being ignited while still in the pores of the tube in contact with the oxygen. This surface ⁷⁵ combustion, as is well known, is very intense and the tube 24 becomes very highly heated.

The screw 16 is then turned, the supply of both oxygen and hydrogen being increased, the oxygen being free to pass readily through the tube 24, and the hydrogen being prevented from passing so freely as it must pass through the pores of the tube 24. The surface combustion increases ⁸⁰ but there is immediately an excess of oxygen delivered through the lower end of the tube. This oxygen is highly heated. In practice I find that it is possible to heat it to 1800° C. or above and I further find that when this highly heated jet of oxygen is ⁸⁵ delivered to the surface of the metal to be cut which is shown diagrammatically at 26, that a narrow opening 27 will be produced.

This narrow opening I believe is due to the high chemical activity of the highly heated oxygen. I find that it is unnecessary to provide the usual heating jet for heating the metal, the jet of super-heated oxygen heating the metal to such a degree that combustion readily starts.

My invention differs from the ordinary method of cutting, in that it is not necessary that the metal to be cut be so highly heated at the starting point. The present method of cutting in which the material 26 is first ¹⁰⁰ ¹⁰⁵ ¹¹⁰

heated up to incandescence at the point of cut is uneconomical as considerable heat is carried away by conduction and as the width of the opening 27 must be considerable to 5 compensate for this conduction. By using super-heated jet of oxygen, I am able to make an extremely narrow cut which is not only more economical but more desirable for many reasons. My invention comprises the 10 use of this super-heated jet of oxygen and I have found that it may be produced by other means such as shown in Figs. 5, 6, and 7 in which 31 is a body and 32 is a cap clamping an insulating refractory tube 33 15 against the body 31, oxygen is supplied through a passage 34 passing through the center of the tube 33 which is heated by means of a heating element 35 supplied with electric current through conductors 36 and 20 37, these conductors being insulated by means of porcelain beads 38. The tube 33 is heated up to the incandescent point by means of the electric current and the oxygen passing through is highly heated by its 25 contact with the walls of this tube. Other means may be provided for heating the oxygen, my invention consisting broadly of the idea of a super-heated oxygen jet. By using a superheated jet of highly active oxygen, I am able to cut materials which the 30 present types of cutting torches will not handle.

I claim as my invention:

1. A process of cutting metals which comprises producing a combustion in a confined space, forcing an excess of oxygen through the space in which said combustion takes place so that said oxygen is highly heated, and forcing a jet of said highly heated 35 oxygen against the metal to be cut.

2. A process of cutting metals which com-

prises producing a combustion in a confined space of oxygen and another gas, forcing an excess of oxygen through the space in which said combustion takes place so that 45 said oxygen is highly heated, and forcing a jet of said highly heated oxygen against the metal to be cut.

3. An apparatus for cutting metal comprising a refractory tube, means for heating 50 said tube above the melting point of any metal, and means for forcing oxygen through said tube against the metal to be cut.

4. An apparatus for cutting metal comprising a refractory tube, means for heating 55 said tube to an incandescent temperature, and means for forcing oxygen through said tube against the metal to be cut.

5. An apparatus for cutting metal comprising a porous refractory tube, means for supplying hydrogen or the like to the space around said tube and at a pressure sufficient to force said hydrogen through the pores of 60 said tube, means for initiating a surface combustion inside said tube, and means for forcing oxygen through said tube against the metal to be cut.

6. An apparatus for cutting metals comprising: walls forming a combustion chamber inside said apparatus; means for initiating a combustion in said chamber; means for passing oxygen in excess of that needed 70 for combustion through said combustion space; and a tip for directing the mixed 75 products of combustion and the excess oxygen under pressure against the metal to be cut.

In testimony whereof, I have hereunto set my hand at Los Angeles, California, this 80 28th day of May, 1920.

CLARENCE J. COBERLY.
